[57] CLAIM

The ornamental design for a lever-operated hoist or puller, as shown and described.

DESCRIPTION

FIG. 1 is a side elevational view of a lever-operated hoist or puller showing my new design, the broken lines are for illustrative purpose only and form no part of the claimed design;

FIG. 2 is a top plan view thereof;

FIG. 3 is a bottom plan view thereof;

FIG. 4 is a left end elevational view thereof; and

FIG. 5 is a right end elevational view thereof.

Fig. 1.

Fig. 2.

Fig. 4.

Fig. 3.
